CLAIM

The ornamental design for a “trim ring lock”, as shown and described.

DESCRIPTION

FIG. 1 is a right, front, top perspective view of a trim ring lock according to our invention;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a bottom elevation view thereof; and,

FIG. 7 is a top elevation view thereof.

The broken lines depict portions of the article that form no part of the claimed design.

1 Claim, 2 Drawing Sheets
